UNITED STATES PATENT OFFICE.

HENRY RESCH, OF BAYONNE, NEW JERSEY, ASSIGNOR TO UNDERWOOD TYPEWRITER COMPANY, OF NEW YORK, N. Y., A CORPORATION OF NEW JERSEY.

TYPE-WRITING MACHINE.

973,385

Specification of Letters Patent. Patented Oct. 18, 1910.

Application filed October 26, 1909. Serial No. 524,631.

To all whom it may concern:

Be it known that I, HENRY RESCH, a citizen of the United States, residing in Bayonne, in the county of Hudson and State 5 of New Jersey, have invented certain new and useful Improvements in Type-Writing Machines, of which the following is a specification.

This invention relates to means for guiding very stiff cards and the like around the cylindrical platens of typewriting machines, and particularly to those devices in which a rod extends over the platen from one end to the other of the platen frame, and carries a 15 series of pendent fingers to hold the card against the platen, the pressure being produced by a spring; the rod with its fingers being detachably mounted on the ends of the platen frame, so that it may be readily 20 removed when not needed. A finger-piece is usually provided to turn the pressure fingers away from the platen for convenience in manipulating the card.

The principal objects of the invention are 25 to improve the means for detachably mounting said rod or bar upon the platen frame, and to secure an even distribution of pressure among a series of guiding fingers, and to simplify the construction and improve the 30 operation of this class of devices.

In the illustrated form of the invention, the upper ends of the card guiding fingers are fixed directly upon a spring-pressed rock shaft, the latter having a key, whereby it 35 may be turned to release the guide fingers, and being mounted at its ends on the platen frame in a novel manner. The ends of the rock shaft are journaled in bearings carried upon the platen frame. The spring or 40 springs for said shaft are, of course, connected between the shaft and the platen frame, so that the platen frame may afford a support for the springs, as they re-act upon the shaft, to cause the fingers to bear against 45 the platen.

In order to provide for the exigency of detaching the device from the platen frame, the springs are connected to the journal box or bearings of the shaft, and said journal 50 boxes are detachably mounted on the platen frame, so that in removing the fingers, the operator takes off also the shaft, the springs and the journal boxes, leaving upon the platen frame nothing but the little brackets 55 in which the boxes are set. The springs are

preferably coiled around the ends of the shaft, and at their inner ends, secured to collars on the shaft, and at their outer ends secured to the journal boxes, the latter having tongues to catch in slots formed in the 60 brackets on the platen frame. To prevent accidental displacement of the device, said brackets are formed with hooks or catches, and said springs are caused to snap the 65 tongues under said hooks or catches.

In the accompanying drawings, Figure 1 is a perspective view of my invention applied to the Underwood type of front stroke writing machine. Fig. 2 is a detail side view partly in section, showing the application of the spring to the pressure finger rock-shaft. Fig. 3 is a detail view showing the manner of detachably seating the attachment on the platen frame. Fig. 4 is a detail cross-sectional view showing the manner of 70 maintaining the springs under tension on the rock shaft and permitting play of the 75 bearings relative to the shaft. Fig. 5 is a detail end view showing the manner of attaching and detaching the device. Fig. 6 is a detail cross sectional view, showing in full 80 lines the normal position of the parts, dotted lines showing the fingers rocked away from the platen to release the work, when the key 85 is depressed.

The usual cylindrical platen 1 of an Underwood front strike writing machine is journaled in the platen frame whose ends are seen at 2. The types 3 strike against the 90 front side of the platen.

For guiding very stiff cards around the platen, I employ a series of fingers 4 pendent from a horizontal rock shaft 5 extending from end to end of the platen frame above the platen. The card is indicated at 6, 95 Fig. 1. The fingers may be jointed together by or formed integral with a plate 7, the latter being fixed to the rock shaft 5 upon its rear side. It will be seen that the fingers descend about vertically, and then at 4*, 100 curve forwardly and downwardly to the platen against which they bear at points directly over the printing line, so as to hold the card firmly back against the platen while it is being printed upon. From their lower 105 ends, the fingers 4 extend upwardly away from the platen, so that they do not cause undue bending of the card around the platen which would give the card a tendency to bulge at the printing line. The bend 4* is 110

so far back that the cards in emerging from the machine are not liable to catch any part of the finger-supporting device.

The row of guiding fingers 4 may extend 5 for nearly the entire length of the platen, as illustrated, and in order to secure an effective pressure of all of these figures, I preferably employ two springs 8, one at each end of the rock shaft or finger-carrying bar 5.

10 The construction at one end of the shaft is the same as at the other end.

Each spring 8 is coiled around the shaft and connected at one end to a set collar 9 on the shaft, which collar may be rotatably 15 adjusted to secure the desired pressure or tension of the spring. The provision of two adjustable springs, one at each end of the shaft, is an advantage, since any inequality in the pressure of the fingers 4 may 20 be corrected by either tightening or weakening one of the springs. The other end of each spring is connected to a part which may be termed a journal box, having a bearing portion 10 in which the shaft turns, and also 25 having a tongue portion 12, slipped into a notch or open slot 13 in a bracket 11 secured upon the top of the platen frame end 2. Relative rotation between the journal box and shaft, whereby the spring may become weakened, is prevented by a pin 15^a projecting 30 into a groove 17 formed in the shaft 5. As a matter of economy, the same spring which presses the fingers against the platen also 35 operates to turn the journal box in a direction to cause the tongue 12 thereof to take or snap under a projection or catch 14 formed upon the bracket at the top of the slot 13, so that accidental removal of the card guide is prevented.

40 The card is inserted and fed forwardly between the platen 1 and the usual bottom pressure rolls 21, and up forwardly in front of the platen. The operator then depresses a key 18, which causes the shaft 5 to turn in 45 its bearings, and the fingers 4 to swing forwardly in front of the platen, shown in dotted lines at Fig. 6. The operator then advances the card and releases the key 18, whereupon the springs 8 cause the fingers 4 50 to snap down upon the card and hold it firmly against the platen close to the place where the card is to be written upon. The provision of two springs, one at each end of the shaft 5, is an advantage, not only be- 55 cause of the practicability of relatively adjusting the springs, but also because the pressure is well distributed among all the fingers, even though the shaft 5 may be of light and weak construction. Moreover, by 60 having the springs at the ends of said shaft, they are brought close to their supports upon the relatively unyielding platen frame, so that liability of bowing or springing the weak shaft 5 is minimized.

65 To detach the device, the operator grips

handles 15 provided upon the journal boxes 10, and pulls said handles forwardly to turn said boxes around the stationary shaft in a direction opposite to the tension of the springs, to enable the tongues 12 to clear 70 the catches 14. Then the operator may lift the handles 15 and withdraw the tongues 12, as seen at Fig. 5, and lift the device away from the machine.

It will be understood that the groove 17 75 in the shaft is of sufficient width to allow a little play of the locking pin 15^a to permit the required turning of the box to disengage it from the catch 14. The pin 15^a may, if desired, be formed upon the inner 80 end of the handle 15, as shown. In replacing the device upon the machine, the finger pieces 15 are first pulled forwardly to make it possible to insert the tongues 12 85 into the slots 13 while the fingers 4 are resting against the platen; and then the device is pressed down, as at Fig. 5, until the tongues seat in the slots 13, and springs 8 snap the tongues under the catches 14.

Owing to the irregularities of manufacture, there is sometimes a slight difference 90 between the length of the platen frame in one machine, and that of the platen frame in another machine; and to compensate for such irregularities, either one or both of the 95 journal boxes may be movable along the rock shaft 5; the groove 17 being of sufficient length to accommodate such movement. The springs 8 exert not only a turning effect upon the shaft 5, but also a pushing 100 effect upon the journal boxes 10, so that the latter are always brought snugly against the brackets 11, regardless of small variations in the distance between said brackets.

In securing the brackets 11 upon the machine, it is desirable to locate them in such a manner that the ends of the fingers 4 shall just clear the types 3. To get this result, the brackets are slotted at 19 to receive their securing screws 20, the slots permitting 110 forward and backward adjustment of the brackets. Adjustment of the brackets backwardly causes the fingers to drag around the platen away from the printing point. Forward movement of the brackets causes the 115 fingers to move down upon the platen closer to the printing point. Therefore, the desired positioning of the fingers can readily be secured; and by moving the brackets forwardly and backwardly relatively to one another, the fingers at one end of the row may be brought into the same relation with the platen as the fingers at the other end of the row.

Having thus described my invention, I 125 claim:

1. In a typewriting machine, the combination with a platen and platen frame, of a paper-holding device including a finger-carrying bar, pressure fingers pendent there- 130

from to hold the paper against the platen, bearings in which the bar is journaled, brackets on the platen frame in which the bearings are non-rotatably seated, a spring secured at one end to a bearing, and adjustable means on the bar, to which the opposite end of the spring is secured, for regulating the tension thereof.

2. In a typewriting machine, the combination with a platen and platen frame, of a paper-holding device including a rock-shaft having pendent fingers to hold the paper against the platen, journal boxes in which the rock-shaft is journaled, a pair of springs, one end of each of which is fixed on the rock-shaft, the remaining ends being secured to the respective journal boxes, and brackets on the platen frame in which the journal boxes are detachably and non-rotatably seated to cause the springs to re-act upon the rock-shaft and press the fingers against the platen.

3. In a typewriting machine, the combination with a platen and platen frame, of a paper-holding device including a finger-carrying bar, pressure fingers pendent therefrom to hold the paper against the platen, bearings in which the bar is journaled, tongues on the bearings, seats on the platen frame into which the tongues are slipped, and by which the tongues are held against rotation, and means connected to a bearing and to the bar, and placed under tension for urging the pressure fingers toward the platen.

4. In a typewriting machine, the combination with a platen and platen frame, of a paper-holding device, including a finger-carrying bar, pressure fingers pendent therefrom to hold the paper against the platen, spring-actuated bearings rotatably and longitudinally shiftable on the bar, seats on the platen frame in which the bearings are non-rotatably held, to cause the spring to re-act upon the bar and press the fingers against the platen, and a pin carried by a spring-actuated bearing and projecting into a groove in the bar to limit the rotary and longitudinal travel of the bearing.

5. In a typewriting machine, the combination with a platen and platen frame, of a paper-holding device, including a finger-carrying bar, pressure fingers pendent therefrom to hold the paper against the platen, spring-actuated bearings rotatably and longitudinally shiftable on the bar, seats on the frame in which the bearings are non-rotatably held, to cause the spring to re-act on the bar for pressing the fingers against the paper, and a stop for limiting the rotary and longitudinal travel of the bearing, relative to the bar.

6. In a typewriting machine, the combination with a platen and platen frame, of a paper-holding device including a finger-

carrying bar, pressure fingers pendent therefrom to hold the paper against the platen, slotted brackets on the platen frame, bearings in which the bar is journaled, the bearings being detachably and non-rotatably seated in the brackets, a spring secured to one of the bearings and to the bar, and placed under tension, and a catch carried by the slotted bracket and under which the bearing is thrust by the spring tension to detain the paper-holding device on the platen frame against accidental displacement.

7. In a typewriting machine, the combination with a platen and platen frame, of a rock-shaft having pressure fingers to hold the paper against the platen, seats on the platen frame, bearings shiftable longitudinally of the shaft to seat in the brackets against rotation, and springs connected to the bearings and to the rock-shaft for urging the fingers toward the platen.

8. In a typewriting machine, the combination with a platen and a platen frame, of a paper-holding device including a finger-carrying bar journaled in bearings on the platen frame and having paper-holding fingers pendent therefrom, the bearings being non-rotatably mounted on the platen frame, and springs connected to the bearings and to the bar respectively and re-acting on the bar to press the fingers against the paper.

9. In a typewriting machine, the combination with a platen and a platen frame, of a paper-holding device including a finger-carrying bar journaled in bearings on the platen frame and having paper-holding fingers pendent therefrom, the bearings being non-rotatably mounted on the platen frame, and separate springs connected to the bearings and to the bar for pressing the fingers against the platen, and relatively adjustable to control and equalize the pressure of the fingers.

10. In a typewriting machine, the combination with a platen and platen frame, of a card guide including a rock-shaft, pressure fingers pendent therefrom, bearings in which the shaft is journaled, the bearings being non-rotatably mounted on the platen frame, and a spring under tension connecting the rock-shaft and one of the bearings to press the fingers against the platen.

11. In a typewriting machine, the combination with a platen and platen frame, of a card guide including a rock-shaft, pressure fingers pendent therefrom, bearings in which the shaft is journaled, the bearings being non-rotatably mounted on the platen frame, and means connected to the bearings and to the rock-shaft and placed under tension by turning the bearings relative to the shaft, for urging the fingers toward the platen.

12. In a typewriting machine, the combination with a platen and platen frame, of a

paper-holding device including a rock-shaft, pressure fingers carried thereby to hold the paper against the platen and separate tension means for urging the shaft in one direction to press the fingers against the platen, the tension means being regulatable to equalize the pressure of the fingers.

13. In a typewriting machine, the combination with a platen and a platen frame, of 10 a paper-holding device, including a finger-carrying bar, fingers pendent therefrom to hold the paper against the platen, bearings in which the bar is journaled, seats on the platen frame into which the bearings are 15 detachably slid, catches on the seats, and a spring connected to a bearing and to the bar respectively for pressing the fingers against the platen, and for snapping the bearings beneath the catches to prevent accidental displacement of the paper-holding 20 device.

14. In a typewriting machine, the combination with a platen and platen frame, of a finger-carrying bar, bearings in which the 25 bar is journaled, a spring connecting one of the bearings and the bar, to press the fingers against the platen, and slotted seats on the platen frame for holding the bearings against rotation, the bearings being rotatable on the bar against the spring tension 30 to effect their insertion in the seats while the fingers are resting against the platen.

15. In a typewriting machine, the combination with a platen and a platen frame, of 35 a card-guide detachably mounted upon said platen frame, a spring, and means for enabling said spring both to press said card guide against the platen and to lock said card guide against detachment from the 40 platen frame.

16. In a typewriting machine, the combination with a platen and a platen frame, of

a card guide detachably mounted upon said platen frame and extending along the platen, a pair of springs, one at each end of said card guide, and means for enabling said springs to press said card guide against the platen and also to lock said card guide at both ends against detachment from the platen frame.

17. In a typewriting machine, the combination with a platen and a platen frame, of 45 a card guide comprising a rod extending along the platen and having card-guiding means extending therefrom, and means for 50 detachably supporting said rod upon said platen frame for rotation; said supporting means including a journal box or bearing member, a spring between the rod and journal box and operating upon the rod to press 55 the card guide against the platen, and a seat or catch in which said journal box is locked by said spring.

18. In a typewriting machine, the combination with a platen and a platen frame, of 60 a card guide comprising a rod extending along the platen and having card-guiding means extending therefrom, and means for 65 detachably supporting said rod upon said platen frame for rotation; said supporting 70 means including a journal box or bearing member, a spring between the rod and journal box and operating upon the rod to press the card guide against the platen, and a seat or catch in which said journal box is locked 75 by said spring, said journal box having a finger piece for rotating it to release it from said catch, for permitting the withdrawal of the card guide from the platen frame.

HENRY RESCH.
